(Cl. D80—11)

Fig. 1.

Fig. 2.

Fig. 3.

Fig. 1 is a perspective view of a refrigerated case embodying my new design, wherein the rear and side not shown are, respectively, the same in appearance as the front and side shown;

Fig. 2 is a top plan view thereof on a reduced scale; and

Fig. 3 is an end view thereof on a reduced scale.

The dominant features of the design reside in the portions shown in full lines.

I claim:

The ornamental design for a refrigerated case, as shown and described.
